(57) **CLAIM**

The ornamental design for a chair, as shown and described.

DESCRIPTION

FIG. 1 is a front elevational view of the chair comprising my new design;

FIG. 2 is a right side elevational view thereof, the opposite side elevational view being a mirror image thereof;

FIG. 3 is a top plan view thereof; and,

FIG. 4 is a rear elevational view thereof.

The broken lines shown in the drawings are for illustrative purposes and form no part of the claimed design.
